CLAIM

The ornamental design for a mosquito killer lamp, as shown and described.

DESCRIPTION

FIG. 1 is a front, right and top perspective view of a mosquito killer lamp showing our new design;

FIG. 2 is a front view thereof;

FIG. 3 is a rear view thereof;

FIG. 4 is a left side view thereof;

FIG. 5 is a top view thereof;

FIG. 6 is a bottom view thereof; and,

FIG. 7 is a rear, left and bottom perspective view thereof.

A right side view is omitted since the right side view is identical to the left side view.
